DEVICE FOR EFFECTIVELY QUENCHING
THE ARC

Albert Lotz, Berlin-Siemensstadt, Germany, assignor to Westinghouse Electric & Manufacturing Company, East Pittsburgh, Pa., a corporation of Pennsylvania

Application May 24, 1933, Serial No. 672,670
In Germany May 24, 1932

13 Claims. (Cl. 200—148)

The invention relates to devices for effectively quenching the electric arcs which result from the separation of the contacts in switches or the melting of fusible cutouts and the like in alternating current circuits.

There exist switches in which the arc is subjected to a powerful blast of compressed air or other gas during the time the current value is zero, and by this means a restoration of the arc with returning voltage is prevented. The blast of compressed air or other gas causes a lengthening of the arc and at the same time removes the ionized current carriers from the space between the electrodes.

In another type of switch two tubular electrodes disposed within a pressure chamber are provided. When the electrodes separate the gas or liquid contained within the surrounding pressure chamber flows through the centrally disposed openings in the electrodes and thereby causes the arc to be lengthened and the ends of the arc to be moved within the hollow electrodes.

The present invention distinguishes from these previously known arrangements wherein a stream of air or other gas under very high pressure is used to lengthen the arc both in structure and method of operation. The arc is established within a tubular passage formed in a suitable member of insulating material. The dimensions of the arc passage are such that the arc is closely confined by the adjacent walls, and the stream of arc extinguishing gas is admitted under moderate pressure, at right angles to the axis of the arc passage. This stream of gas

tends to press the arc against the opposite wall of the arc passage. Movement of the arc in this direction is, however, definitely limited, due to the presence of the confining walls of the arc passage, and in addition, it is impossible, because of the proportioning of the arc passage, for the out-flowing stream of gas to bow out the arc as is done in the prior art structures. By this arrangement, any substantial lengthening of the arc is prevented, and in addition, the arc is held in a position where the outflowing stream of gas can most effectively produce the desired extinction.

In the accompanying drawing I have illustrated several embodiments of my preferred invention.

Figure 1 shows the invention as applied to a fusible cutout. The fuse wire *f* is clamped between electrodes *a* and *b* and extends through a tubular opening *d* formed within an insulating body *c*. When the wire *f* fuses, due to overload,

an arc is established in the opening or arc passage *d*. Perpendicular to passage *d*, is a channel *e* which passes through the insulating body *c*, and through this channel, the moment an arc is formed, a gas such as air, carbon dioxide, or the like is blown. The dimensions of the arc passage *d* within the insulating body *c* are such that the arc is forced against the opposite wall in the passage *d* and, by virtue of the confining action of that wall, is prevented from lengthening. The resulting intimate co-mingling of the arc and the fresh un-ionized gas which is forced into the arc passage through the channel *e* effects the extinguishment of the arc at the first zero point in the current wave. The fresh un-ionized gas blown into the arc passage vents through either end of the arc passages, and by carrying away all the charged bodies from the arc passage, prevents a restriking of the arc with the returning voltage.

Figs. 2 and 3 show a switch according to my invention in the closed and opened positions, respectively. The moving contact *a* is adapted to move through an arc passage *d* formed within an insulating body *c*, and when the breaker is in the closed circuit position, the right hand end of the moving contact *a* is adapted to abut against the cooperating contact surfaces of the fixed contact *d*. The cross sectional dimensions of the arc passage *d* and the moving contact *a* are such that the conduit passage *e* utilized for introducing the arc extinguishing gas into the arc passage is substantially closed when the circuit is in the closed circuit position.

During the circuit opening operation the moving contact *a* is moved from the position shown in Fig. 2 to the position shown in Fig. 3. This movement draws an arc longitudinally within the arc passage *d* and at the same time allows a quantity of an arc extinguishing gas to be forced into the arc passage through the conduit opening *e*. The confining action of the arc passage *d* prevents the resulting stream of gas flowing therein from bowing out and thereby lengthening the arc, and since the passage is open at either end when the switch is in the open circuit position, the fresh un-ionized gas flowing through the arc passage effectively removes all of the current carrying bodies so as to prevent the restriking of the arc.

Figs. 4, 5 and 6 show a switch wherein the cross sectional area of the arc passage may be varied according to the physical dimensions of the arc which is established therein. The moving contact *a* and the fixed contact *b* are respectively

similar to the contacts *a* and *b* of the switch shown in Figs. 1 and 2. The arc passage *d* wherein the moving contact *a* moves is defined by a pair of substantially parallel wall members *c* and is adapted to be closed at the lower end by a rectangular member *f* having a conduit opening *e* therein. The upper surface of the arc passage *d* is defined by a movable slider member *h* of insulating material which is biased toward the member *f* by means of a pair of suitable springs *i*.

When the switch is in the closed circuit position the slider member *h* bears against the upper surface of the rectangular moving contact *a*. As soon as the moving contact *a* disengages the arc passage *d* during the circuit opening operation, the slider *h* moves downwardly under the influence of its biasing springs so as to restrict the cross sectional area of the arc passage. The amount of this restricting depends upon the physical dimensions of the arc, which is to say that it depends upon the magnitude of the arc current, since one is a function of the other. By this arrangement a close confinement of the arc within the arc passage *d* is assured, and the arc is prevented from bowing out and moving away from the in-coming stream of arc extinguishing gas which flows through the conduit *e* at right angles to the longitudinal axis of the arc passage. As a result, the arc is prevented from being lengthened by the in-flowing stream of gas, and a rapid extinguishment thereof is effected.

The length of the arc passage *d*, which is determined by the dimensions of the insulating body *c*, depends upon the voltage and the characteristics of the circuit with which the switch is to be used. If this voltage is very high, it is possible to arrange a plurality of devices such as that shown in Figs. 4, 5, and 6 in such manner that the arc passages *d* in the several units shall 40 align one with the other. If this is done, the interruption of the arc is greatly facilitated, due to the fact that individual sections thereof are each subjected to a separate stream of gas which enters the arc passage of each of the several devices substantially at right angles to the longitudinal axis thereof. In other words each device acts to effect the extinguishment of a section of the arc. It is, of course, necessary that the insulating body *c* be so dimensioned that flash-over 50 will not occur due to the presence of ionized gas or abnormal circuit voltage.

The arc passage *d* within the insulating body *c* may be of any cross section, and the body *c* may be formed of any suitable material, it being important merely that the material is insulating. Porcelain, molded material, fibre impregnated with artificial resin (hard paper, linen), alumina or steatite have all been used with satisfactory results. If metal is used in any portion of the 60 wall defining body *c*, it is necessary that the surface thereof which is exposed to the arc shall be provided with a layer of insulating material capable of withstanding the normal circuit voltage. It is possible to use wood (particularly oak 65 or beech) or oil impregnated wood for defining the walls of the arc passage.

In the two structures illustrated there is only one conduit or channel *e* through which the arc extinguishing gas is introduced into the arc passage. It may be desirable to provide an annular space disposed around the arc passage *d* which is provided with a number of radially directed borings connected with the arc passage. If this is done, the arc extinguishing gas may be caused 75 to flow into the arc passage at a plurality of

points and the operation will thereby be somewhat improved.

For cooling purposes, the arc passage wherein the arc is formed may be surrounded by a water jacket, the simplest means of accomplishing this being the provision of an annular passage within the walls of an insulating body, and if desired, small channels may be provided leading from this space into the arc passage itself in such manner that the cooling water may percolate 10 down through these channels so as to cover the internal surface of the arc passage with a film of water.

Fig. 7 illustrates schematically one method of connecting a circuit interrupter according to my invention into an electrical circuit. As shown, the moving contact *a* of the breaker which is electrically connected to one side of the power circuit, is adapted to move within a suitable guide means *g*, and is biased to the open circuit position by a spring *h* associated with the breaker operating solenoid *k*. A gas reservoir is provided for producing the blast of arc extinguishing gas through the arc passage *d* within the insulating body *c*, and the liberation of this gas is controlled 20 by an electromagnetic valve. An overload relay electrically connected in the power circuit is provided for controlling the operation of the switch and the electromagnetic valve. The breaker operating solenoid *k* is normally energized in order 30 to hold the contacts in the closed circuit position.

Upon the occurrence of an overload, the overload relay moves to deenergize the electromagnetic valve and the breaker operating solenoid *k* thereby making it possible for the biasing spring *h* to 35 move the contacts to the open circuit position. At the same time the electromagnetic valve operated to cause a definite quantity of the gas contained within the gas reservoir to flow through the arc passage, thereby effecting the extinguishing 40 of the arc which is drawn therein.

It will thus be seen that I have provided an improved circuit interrupter wherein the arc which is established incident to the opening of the connected circuit is extinguished through the agency of a flowing stream of un-ionized gas. The structure of my invention differs from the devices already known to the art in that the arc is so confined that the stream of arc extinguishing gas does not effect a substantial lengthening 50 of the arc, but intimately co-mingles with the arc and thereby operates much more efficiently in effecting the extinguishment thereof.

I claim as my invention:

1. In a circuit interrupter, means at least partially of insulating material for defining the walls of an arc passage having a length which is at least several times its greatest cross sectional dimension, means for establishing an arc within said arc passage, and means including a conduit which opens into said arc passage intermediate its ends for causing a quantity of arc extinguishing fluid to flow through said arc passage during each circuit interrupting operation in order to effect the extinguishment of said arc, said arc passage being open at least at one end when said interrupter is in the open circuit position, and at least a portion of said wall defining means comprising a member of insulating material which is movable to vary the cross sectional area of said arc passage during the circuit opening operation so as to prevent said quantity of fluid from bowing said arc.

2. In a circuit interrupter, means at least partially of insulating material for defining the walls

55

60

65

70

75

of an arc passage having a length which is at least several times its greatest cross sectional dimension, means for establishing an arc within said arc passage, and means including a conduit 5 which opens into said arc passage intermediate its ends for causing a quantity of arc extinguishing fluid to flow through said arc passage during each circuit interrupting operation in order to effect the extinguishment of said arc, said arc

10 passage being open at both ends when said interrupter is in the open circuit position and, except for said conduit, being otherwise closed, said fluid being introduced into said passage under pressure and at a substantial angle to the longitudinal 15 axis thereof, and at least a portion of said wall defining means comprising a member of insulating material which is movable to vary the cross sectional area of said arc passage in response to the physical dimensions of the arc which is established therein during the circuit opening operation, thereby preventing said quantity of fluid from bowing or otherwise lengthening said arc.

3. In a circuit interrupter, means at least partially of insulating material for defining the walls 25 of an arc passage having a length which is at least several times its greatest cross sectional dimension, means for establishing an arc within said arc passage, means including a conduit which opens into said arc passage intermediate its ends 30 for causing a quantity of arc extinguishing fluid to flow through said arc passage during each circuit interrupting operation in order to effect the extinguishment of said arc, said arc passage being open at least at one end when said interrupter is in the open circuit position, and means 35 for varying the cross sectional area of said arc passage in response to the physical dimensions of the arc which is established therein during the circuit opening operation, thereby preventing said 40 quantity of fluid from bowing or otherwise lengthening said arc, said area varying means comprising a member movable into said arc passage during the operation of said interrupter and means for moving said member in such manner that the 45 cross sectional area of said arc passage shall be proportional to the physical dimension of the arc which is established therein.

4. In a circuit interrupter, a pair of oppositely disposed, spaced plates formed at least partially 50 of insulating material and each of which has a considerable surface area, for defining two of the walls of an arc passage, means for establishing the arc incident to each opening operation of said interrupter within said arc passage, and 55 means for defining the other walls of said arc passage, including a member slidably edgewise in the plane of said arc between said pair of opposed plate members to cause the dimensions of said arc passage to be varied in response to the current magnitude of the arc which is established 60 therein during the operation of the said interrupter.

5. In a circuit interrupter, a pair of substantially flat plates of insulating material, positioned 65 in parallel planes and spaced some distance from each other, for defining two of the opposed walls of a rectangular arc passage, means of insulating material for defining the other two walls of said arc passage in order that said passage shall be substantially completely enclosed except at one or more of the ends thereof during the operation 70 of said interrupter, means for establishing the arc incident to each opening operation of said interrupter within said arc passage, said means for defining the other two walls of said arc pas-

sage including a flat member of insulating material slidably edgewise in the plane of said arc between said opposed plate members to vary the dimensions of said arc passage in accordance with the current magnitude of the arc which is established therein, and means for resiliently biasing said slidably member to a position where the cross sectional area of said arc passage is reduced to a predetermined minimum. 5

6. In a circuit interrupter, a pair of substantially flat plates of insulating material, disposed in parallel planes and spaced some distance from each other, for defining two of the opposed walls of a rectangular arc passage, means for defining the other two walls of said arc passage in order 10 that said passage shall be substantially completely enclosed except at the ends thereof during the operation of said interrupter, means for establishing the arc incident to each opening operation of said interrupter within said arc passage, 15 said means for defining the other two walls of said arc passage including a member of insulating material slidable between said opposed plates to vary the dimensions of said arc passage in accordance with the current magnitude of the arc which is established therein, and means, including a conduit which opens into said arc passage intermediate the ends thereof, for causing a quantity of arc extinguishing fluid to flow through said arc passage during each circuit interrupting operation, 20 said slidably member causing the physical dimensions of said arc passage to closely approximate the physical dimensions of said arc at all times, thereby effecting intimate contact between said arc extinguishing fluid and the arc. 25

7. In a circuit interrupter, means, at least partially of insulating material, for defining the walls of an arc passage having a length which is at least several times its greatest cross section dimension, means for establishing the arc incident 40 to each opening operation of said interrupter within said arc passage, means including a conduit which opens into said arc passage intermediate its ends, for causing a quantity of arc extinguishing fluid to flow through said arc passage 45 during each circuit opening operation in order to effect the extinguishment of said arc, and means for varying the cross sectional area of said arc passage in response to the physical dimensions of the arc which is established therein during the 50 operation of said interrupter, in order to assure intimate contact between said arc extinguishing fluid and said arc. 55

8. In a circuit interrupter, means, at least partially of insulating material, for defining the walls of an arc passage having a length which is at least several times its greatest cross sectional dimension, means for establishing the arc incident to the opening of said interrupter longitudinally within said arc passage, and means, including a conduit which opens into said arc passage intermediate its ends, for causing a quantity of arc extinguishing fluid to flow through said arc passage during each circuit interrupting operation in order to effect the extinguishment of said arc, said arc passage being open at least at one end when said interrupter is in the open circuit position and except for said conduit being otherwise substantially completely enclosed, said wall defining means including a member of insulating material which is movable to vary the cross sectional area of said arc passage in response to the physical dimensions of the arc which is established therein during the operation of said inter- 60 65 70 75

- rupter, thereby assuring intimate contact between said arc extinguishing fluid and said arc.
9. In a circuit interrupter, means at least partially of insulating material for defining the walls of an arc passage having a length which is at least several times its greatest cross sectional dimension, means for establishing the arc incident to the opening of said interrupter longitudinally within said arc passage, means, including a conduit which opens into said arc passage intermediate its ends, for causing a quantity of arc extinguishing fluid to flow through said arc passage during each circuit interrupting operation, in order to effect the extinguishment of said arc, said arc passage being open at both ends when said interrupter is in the open circuit position and except for said conduit means being otherwise substantially completely enclosed, said fluid being introduced into said passage under pressure, and at least a portion of said wall defining means comprising a resiliently biased member of insulating material which is movable to vary the cross sectional area of said arc passage in response to the physical dimensions of the arc which is established therein during the operation of said interrupter.
10. In a circuit interrupter, means at least partially of insulating material for defining the walls of an arc passage, means for establishing the arc incident to each opening operation of said interrupter within said arc passage, a source of arc extinguishing fluid external to the arc passage, means for causing a blast of said arc extinguishing fluid to be moved into and to flow through said arc passage longitudinally thereof to effect the extinguishment of said arc, said arc passage being open at least at one end thereof during each arc extinguishing operation and being otherwise substantially completely enclosed, and movable means of insulating material for varying the cross sectional area of said arc passage intermediate said arc establishing means in response to the physical dimensions of the arc which is established therein during the operation of said interrupter in order to assure intimate contact between said arc extinguishing fluid and said arc.
11. In a circuit interrupter, means at least partially of insulating material for defining the walls of an arc passage having a length which is at least several times its greatest cross sectional dimension, means for establishing the arc incident to each opening operation of said interrupter within said arc passage, a body of arc extinguishing fluid, means including a conduit which opens into said arc passage intermediate its ends for causing a quantity of said arc extinguishing fluid to be moved into and to flow through said arc passage during each circuit opening operation to effect the extinguishment of said arc, said arc passage being open at least at one of its ends during each arc extinguishing operation and except for said conduit being otherwise substantially completely enclosed, said arc extinguishing fluid being introduced into said arc passage under pressure and at a substantial angle to the longitudinal axis thereof, and means for varying the cross sectional area of said arc passage in response to the physical dimensions of the arc which is established therein during the operation of said interrupter in order to assure intimate contact between said arc extinguishing fluid and said arc.
12. In a circuit interrupter, means at least partially of insulating material for defining the walls of an arc passage having a length which is at least several times its greatest cross sectional dimensions, means for establishing the arc incident to each opening operation of said interrupter longitudinally within said arc passage, a body of arc extinguishing fluid, and means including a conduit which opens into said arc passage intermediate its ends for causing a quantity of said arc extinguishing fluid to flow through said arc passage during each circuit interrupting operation in order to effect the extinguishment of said arc, said arc passage being open at least at one end during each arc extinguishing operation and except for said conduit means being otherwise substantially completely enclosed, said fluid being introduced into said arc passage under pressure and at a substantial angle to the longitudinal axis thereof, and at least a portion of said wall defining means comprising a resilient biased member of insulating material which is movable to vary the cross sectional area of said arc passage in response to the physical dimensions of the arc which is established therein during the operation of said interrupter.
13. In a circuit interrupter, a pair of substantially flat plates of insulating material disposed in parallel planes and spaced some distance from each other for defining two of the opposed walls of an arc passage having the general form of a rectangular prism, means for establishing the arc incident to each opening operation of said interrupter within said arc passage, means for defining the other two walls of said arc passage including a member of insulating material slidably between said opposed plates to vary the dimensions of said arc passage in accordance with the physical dimensions of the arc which is established therein, and means for causing a blast of arc extinguishing fluid to flow through said arc passage during each circuit interrupting operation to effect the extinction of said arc, said arc passage being substantially completely enclosed except at the ends thereof during each arc extinguishing operation, said slidably member causing the physical dimensions of said arc passage to closely approximate the physical dimensions of said arc at all times thereby effecting intimate contact between said arc extinguishing fluid and said arc.

ALBERT LOTZ.
